UNITED STATES PATENT OFFICE.

WILLIAM ROLAND SMITH, OF TERRELL, TEXAS.

SHOE-PASTE APPLIER.

SPECIFICATION forming part of Letters Patent No. 720,079, dated February 10, 1903.

Application filed June 28, 1902. Serial No. 113,616. (No model.)

To all whom it may concern:

Be it known that I, WILLIAM ROLAND SMITH, a citizen of the United States, residing at Terrell, in the county of Kaufman and State of Texas, have invented a new and useful Shoe-Paste Applier, of which the following is a specification.

This invention relates to a device for applying paste to shoes previous to being polished.

The object of the invention is to provide a device of the character specified which shall be thoroughly efficient in operation for the purpose designed and which may readily be supplied with a paste-applying element when necessary. As will hereinafter appear, the device of this invention will enable the user to apply the paste without soiling his hands or garments, and, further, a saving in the paste will be effected, for the reason that any that remains on the device after use may be utilized in a subsequent operation, whereas when paste is applied by means of a piece of cloth, as usual, there is always more or less waste of the paste.

A further object is to effect positive assemblage of the paste-applying element with its holder without the employment of supplemental fastening devices, thereby cheapening the cost of production of the device as a whole and rendering the application to the holder of a new paste-applying element an easy matter.

With these and other objects in view, as will appear as the nature of the invention is better understood, the same consists in the novel construction and combination of parts of a shoe-paste applier, as will be hereinafter fully described and claimed.

In the accompanying drawings, forming a part of this specification, and in which like numerals of reference indicate corresponding parts, there is illustrated one form of embodiment of the invention capable of carrying the same into practical operation, it being understood that the elements therein exhibited may be varied or changed as to shape, proportion, and exact manner of assemblage without departing from the spirit thereof, and in these drawings—

Figure 1 is a view in perspective of a paste-applier constructed in accordance with the

present invention. Fig. 2 is a view in side elevation of the head that carries the paste-applier removed from the handle.

55

Referring to the drawings, 1 designates the holding element, 2 the paste-applying element, and 3 the handle.

The holding element is constructed of wire and comprises an intermediate coiled portion 60 4 and terminal arms 5, which are connected by being twisted together in two or more turns, as shown at 6. The paste-applying element is made from any suitable textile fabric, such as cotton or cloth, wound into a roll and 65 passed through the portion 4, and is held positively associated therewith by the curve imparted thereto when the arms are associated, as clearly shown in Fig. 2. In other words, when the arms are disconnected the coils of the 70 portion 4 are disposed parallel with each other, and thus a straight bore is presented to receive the paste-applying element; but when the arms are connected the coiled portion is bent in a curve, as clearly shown in Fig. 2, 75 thereby in an obvious manner effecting a pinching or biting action upon the paste-applying element. It will thus be seen that the said element will be positively held associated with the coiled portion 4 without the employment of supplemental fastening devices for the purpose and, further, that by disconnecting the terminals of the arms pressure will be removed from the paste-applying element to permit application of a new one when necessary.

80 The handle 3 may be made of any suitable material, preferably of wood, and may bear suitable advertising matter, if so desired.

85 The use of the device will be obvious. 90 Either end of the paste-applying element may have the paste associated with it by dipping such end in the paste, and the paste is then rubbed upon the shoe in the usual manner, effecting even distribution thereof over the 95 shoe.

While the device of this invention is exceedingly simple of construction, it will be found thoroughly efficient and durable in use for the purpose designed and may be manufactured and sold at a price that will permit of its being given away as an advertising medium.

100 Having thus fully described my invention,

what I claim as new, and desire to secure by Letters Patent, is—

1. A device of the character specified, comprising a paste-applying element, and a holding member having a curved intermediate tubular coiled portion to house the said element.
2. A device of the character specified, comprising a paste-applying element and a holding member having terminal connected arms and a curved intermediate coiled portion to house the said element.
3. A device of the character specified, com-

prising a paste-applying element, a holding member therefor having terminal arms held 15 associated by being twisted together and a curved intermediate coiled portion to house the said element, and a handle for receiving the twisted portions of the arms.

In testimony that I claim the foregoing as 20 my own I have hereto affixed my signature in the presence of two witnesses.

WILLIAM ROLAND SMITH.
